RIBBON REEL

Application filed April 8, 1931. Serial No. 528,572.

This invention relates to improvements in ribbon reels and has particular reference to a reel upon which ribbon is wound in hank form.

5 An object of the invention is to provide an improved reel of practical and inexpensive construction wherein the ends of the reel, about which the ribbon is wound and which provide supports for the ribbon to retain 10 the same in its wound condition, constitute a part of the single blank of material from which the reel is constructed.

The above and other objects will appear more clearly from the following detailed 15 description, when taken in connection with the accompanying drawing, which illustrates a preferred embodiment of the inventive idea.

In the drawing—

20 Figure 1 is a plan view of the blank from which the reel is made;

Figure 2 is a side elevation of the reel in its completed form with a hank of ribbon wound thereon;

25 Figure 3 is an enlarged longitudinal section of the reel before the ribbon is wound thereon;

Figure 4 is a similar section with the ribbon in place; and

30 Figure 5 is a section on the line 5—5 of Figure 4.

Referring to Figure 1, there is shown a blank which may be of any suitable material, such as fairly stiff paper or light card-

35 board, and from which the reel is formed. The blank is cut and scored to provide the opposed complementary side sections 6 and 7 and an intermediate ribbon-supporting edge section 8, the latter extending along

40 portions of the peripheries of said side sections and terminating at its ends in extensions 9 which form end supports for the ribbon when the latter is wound upon the finished reel, as will appear in the course

45 of the description. Outer ribbon-supporting edge sections 10 and 11, similar to the section 8, are formed along the outer edges of the sections 6 and 7, respectively, and when the blank is folded on the indicated

50 dotted lines, said sections 10 and 11 are

overlapped and secured together by a suitable adhesive. Either of the sections 10 or 11, in this instance the former, is provided at its ends with extensions 12 similar to the extensions 9 and opposed thereto 55 when the reel is in its assembled position, as shown in Figure 3.

Before the blank is folded to form the reel, the side sections 6 and 7 each has cut therein adjacent its rounded ends the openings 13 which align with the adjacent openings in the other section, when the reel is assembled, so as to receive a rod or pin (not shown) which is utilized while the ribbon 14 is being wound upon the reel. As this 60 winding operation is started, the first turn or convolution of the ribbon engages the rods or pins at the ends of the reel and at the same time flexes the opposed extensions 9 and 12 inwardly toward each other, as indicated in dotted lines in Figure 3, the position of the openings relative to said extensions being such that the latter will assume, under pressure of the ribbon thereagainst, an arcuate contour substantially in alignment with the portions of the surfaces of 65 said rods which are engaged by the ribbon. Thus, while the ribbon is being wound upon the reel, the rods and extensions form supports therefor and cause the superimposed 70 layers to assume a rounded form at the ends of the reel. After said rods are withdrawn from the openings 13 at the conclusion of the winding operation, the extensions 9 and 12 will continue to provide supports for the 75 ribbon, as illustrated in Figure 4, by reason of the outward pressure of the flexed extensions against the innermost convolution of the wound ribbon, and the extremities of the side sections 6 and 7, beyond which the 80 layers of ribbon do not extend, will maintain said layers in superimposed relation. To further prevent displacement of the 85 layers of ribbon between the ends of the reel, a flexible band 15, which may consist of a 90 strip of paper, is secured around the ribbon and reel transversely thereof.

What is claimed is:

1. A ribbon reel comprising edge sections 95 upon which a length of ribbon is to be 100

wound, and opposed extensions at each end of said edge sections flexed toward each other by said ribbon to form arcuate supports therefor.

5 2. A ribbon reel comprising side and edge sections, said side sections having openings therein adjacent their ends, and said edge sections having spaced opposed ribbon-supporting extensions at their ends flexed to 10 ward each other by a ribbon wound thereon so as to assume an arcuate formation the contour of which substantially aligns with a portion of the edge of the adjacent opening.

15 3. A ribbon reel formed from a single blank of flexible material scored to provide side and edge sections, and flexible extensions at each end of said edge sections flexed toward each other by a ribbon wound on the 20 latter sections to constitute supports for said ribbon which exert an outward pressure thereon.

In testimony whereof, we have affixed our signatures.
